UNITED STATES PATENT OFFICE.

HENRY BRUNS, OF ST. LOUIS, MISSOURI.

DRAFT-RIGGING FOR RAILWAY-CARS.

SPECIFICATION forming part of Letters Patent No. 718,563, dated January 13, 1903.

Application filed October 26, 1901. Serial No. 80,112. (No model.)

To all whom it may concern:

Be it known that I, HENRY BRUNS, a citizen of the United States, residing in the city of St. Louis, in the State of Missouri, have invented 5 certain new and useful Improvements in Draft-Rigging for Railway-Cars, of which the following is a full, clear, and exact description, reference being had to the accompanying drawings, forming part of this specification. 10

My invention relates to a draft-rigging for use on railway-cars, the principal object of the invention being to so construct a draft-rigging that the draw-head thereof is capable 15 of having swinging motion imparted thereto by movement of the truck-bolster of the car, so that the draw-head will move in correspondence to said bolster when the car-truck is rounding curves, thereby preventing liability 20 of the draw coupler-heads being disengaged from each other.

My invention consists in features of novelty hereinafter fully described, and pointed out in the claims.

25 Figure I is a top or plan view of my rigging. Fig. II is a vertical longitudinal sectional view taken on line II II, Fig. I. Fig. III is an enlarged detail perspective view of one of the filler-washers applied to the draft-rod carriers. Fig. IV is an inverted view of the rigging. Fig. V is an enlarged vertical sectional view taken on line V V, Fig. IV. Fig. VI is a detail sectional view taken on line VI VI, Fig. V. Fig. VII is a detail sectional view 30 taken on line VII VII, Fig. IV. Fig. VIII is a detail perspective view of one of the draft-rod carriers.

35 1 designates the main sills, and 2 the sub-sills, that extend longitudinally of the car to 40 which my rigging is applied.

45 3 is the end sill, fitted to the ends of the main and sub sills.

40 4 designates the body-bolster, fixed to the sills 1 and 2, and 5 is the truck-bolster, on 45 which the body-bolster is mounted.

50 6 designates draft-rod carriers, mounted in pairs and having wings 7, that are connected to the sills 1 and 2 by bolts 8, that pass vertically through the carrier-wings 7 and the 55 sills to which they are fitted. Each of the carriers 6 has an upwardly-extending tongue 9, that fits between the sills 1 and 2 and is

held by the transverse bolt 10, passing therethrough and through the sills. On the forward end of each tongue 9 is a stud 11, that 55 enters a recess in the rear face of the end sill 3 (see Fig. II) and prevents lateral movement of the carriers and sills. On the upper face of the carrier-wings 7 are ribs 12, that fit in recesses in the lower faces of the sills 1 and 60 2 and serve to strengthen the connection between said carriers and the sills. Each carrier 6 is provided with a box 13, located at the under side thereof and containing pockets 14. (See Fig. II.) Each of the carriers 6 65 is tapered at its outer end, as seen at 15, Figs. II, IV, and VIII, and contains a non-circular cavity 16, to which more particular reference will hereinafter be made.

17 designates draft-rods mounted in and 70 extending through the pairs of draft-rod carriers 6 and having mounted thereon draft-springs 18, that occupy the pockets 14 in said carriers.

19 is an equalizer located beneath the sills 75 1 and 2 and having bores extending therethrough, through which the draft-rods 17 pass. At the sides of said equalizers are bosses 20, that enter the pockets 14 in the draft-rod carriers and bear against the draft-springs 18. (See Fig. II.)

21 designates the draw-bar, provided with the draw-head coupler 22. The draw-bar is 80 rockingly mounted in a stirrup 23, suspended beneath the end sill 3 by bolts 24, and seated 85 on said stirrup is a chafing-plate 25. Within the stirrup 23 are saddle-blocks 26, that bear against the sides of the draw-bar 21 and are held by bolts 28, that pass vertically through said stirrup and the chafing-plate 25, as seen 90 in Figs. V and VI, this construction being adopted to permit free rocking motion of the draw-bar. The free end of the draw-bar 21 is slotted, as shown in Fig. VII, and mounted in the slot therein are antifriction-rollers 29 95 and 31, adapted for rotation on their pivot-pins 30 and 32, the roller 29 being positioned in front of the equalizer 19 and the roller 31 being positioned in the rear of said equalizer. One of said rollers is of greater diameter than 100 the other, that 29 being shown in the drawings of the greater diameter, and they are interchangeable, so that their positions may be reversed in order that the draw-bar may

be moved inwardly or outwardly to suit exigencies, according as greater or less projection of the draw-bar coupler may be desirable or necessary. To illustrate, if the draw-bar 5 coupler is to be projected to the greatest extent the rollers are positioned, as shown in the drawings, with the roller 31 at the rear of the equalizer, whereas if it is desired to obtain the least projection the rollers are reversed, so that the larger roller 29 is positioned at the rear of the equalizer. This arrangement is of merit in connection with the natural wear of the parts, inasmuch as the rollers can be reversed at any time to suit 10 conditions.

33 designates a swing-bar having in its forward end an open slot 34 and pivotally mounted in a slotted hanger 35, that is fixed to the car-sills 1 and 2. The forward slotted 20 end of the swing-bar 33 is fitted to the bolt 32, seated in the rear end of the draw-bar, so as to have rocking connection therewith and at the same time be of ready disconnection from the draw-bar. The swing-bar 33 extends rearwardly from the hanger 35 and is 25 connected to the truck-bolster 5 by links 36 to provide for the communication of motion from said bolster to said swing-bar.

The purpose of tapering the outer ends of the 30 draft-rod carrier-boxes 13 at 15, as hereinbefore mentioned, is to provide an inclined surface at the front ends of said boxes, which will permit of the boxes riding upwardly onto the draft-rigging at the facing end of an adjacent joining car in the event of a collision, so that said boxes and the carriers equipped therewith will not be broken or severed from connection with the sills to which they are attached. The carriers 6 are all of the same 35 construction, being tapered at their ends, so as to be interchangeable, and in order to provide for the mounting of the draft-rods 17 therein it is necessary to utilize means assembled with the rear carrier-boxes 13, 40 against which the nuts of said draft-rods may have bearing. This means I provide by the introduction of filler-washers 37, one of which is shown in detail in Fig. III, the said washers having a flat outer face 38 and a tapering inner face 39, corresponding in shape to the taper 15 of the carrier-boxes. Each washer has a non-circular protuberance 40, that is adapted to fit in the non-circular cavity 16, contained by a box 13, so that the washers 45 will fit snugly to the ends of said boxes and be prevented from rotation therein, while presenting the flat face 38 for the bearing of the nuts of the draft-rod 17, in order that said nuts may be readily turned on said draft-rods.

60 In the practical operation of the draft-rigging any movement of the truck-bolsters 5 is communicated, through the links 36, to the swing-bar 33 and therefrom to the draw-bars 21, so that said draw-bars will swing correspondingly to the movement of the truck-bolster and always maintain the draw-bar 65 coupler-heads in connection with each other

between the adjoining cars of a train irrespective of the contour of the track on which the truck-wheels of the cars travel. The slotted inner end of the draw-bar swings freely on the equalizer 19 and continues this engagement with said equalizer through the medium of the antifriction-rollers 29 and 31, whereby connection to the draft-rods 17 and 75 the draft-springs 18 is continually maintained to exercise the functions of said parts.

I claim as my invention—

1. In a draft-rigging, the combination with the car-truck and the car-body, of a draw-head adapted for swinging movement, a swing-bar pivoted to the car-body and connected to the rear end of the draw-head, and connections between the swing-bar and the truck to control the movement of the draw-head, substantially as described.

2. In a draft-rigging, the combination with the car-truck and the car-body, of a draw-head capable of swinging movement, a swing-bar pivotally carried by the car-body, a pin-and-slot connection between the draw-head and swing-bar, and connections between the swing-bar and the truck to control the movement of the draw-head, substantially as described.

3. In a draft-rigging, the combination of a swingingly-mounted draw-bar, a swing-bar pivotally intermediate its ends connected at one side of its pivot with the rear end of the draw-bar, and a pair of links connecting said swing-bar at the other side of its pivot with the truck to communicate movement from the truck to the draw-bar, substantially as described.

4. In a draft-rigging, the combination with a truck-bolster and swingingly-mounted draw-bar, of links pivoted to said bolster, and a swing-bar pivoted intermediate its ends, and loosely connected to said links at one side of its pivot, and having loose engagement with said draw-bar at the other side of its pivot, to communicate the movement of said bolster to said draw-bar to swing the draw-bar laterally, substantially as described.

5. In a draft-rigging, the combination with draft-rods and springs mounted thereon, of a centrally-curved equalizer mounted on said draft-rods, a draw-bar movable longitudinally on the equalizer-bar, and antifriction-rollers carried by said draw-bar adapted to bear against said equalizer at its forward and rear edges, substantially as described.

6. In a draft-rigging, the combination of draft-rod-supporting means, draft-rods, springs mounted on said rods, a centrally-curved equalizer mounted on said rods adapted to bear against said springs, a swinging draw-bar movable longitudinally on said equalizer, and antifriction-rollers mounted in said draw-bar and adapted to bear against the curvatures at the forward and rear edges of said equalizer, substantially as described.

7. In a draft-rigging, the combination with draft-rods and springs mounted thereon, of

an equalizer mounted on said draft-rods, a draw-bar movable longitudinally on the equalizer-bar, and a pair of antifriction-rollers of differing diameter carried by said draw-bar and adapted to bear against said equalizer at the front and rear thereof, substantially as described.

8. In a draft-rod carrier, the combination of a box having a tapering end and a non-circular cavity therein, a washer having a tapered inner face adapted to fit the tapered end of said box, and a flat outer face and a non-circular protuberance on said washer adapted to fit in the non-circular cavity in said box, substantially as described.

9. In a draft-rod carrier, the combination of a draft-rod receiving-box, horizontal wings by which said carrier is attached to the car-sills, a vertical tongue projecting above said box and adapted to seat between the sills of the car, and ribs carried by the horizontal wings and adapted to seat in the car-sills.

10. In a draft-rigging, the combination with main sills, subsills, and an end sill, of a draft-

rod carrier provided with a draft-rod receiving-box, horizontal wings by which said carrier is attached to the main and the subsill, a vertical tongue projecting above said box between said main and sub sills, a lug carried by said tongue, and adapted to seat in said end sills, and ribs carried by the horizontal wings and adapted to seat in the main and sub sills.

11. In a draft-rigging, the combination of an equalizing-bar, bosses upon opposite sides of the equalizing-bar at each end thereof, draft-rod carriers formed with pockets into which the bosses extend and are guided, draft-rods connected with the equalizer-bar and with the rod-carriers, and springs mounted in the pockets of the carrier.

In testimony whereof I have hereunto set my hand this 23d day of October, 1901.

HENRY BRUNS.
